US00D501055S

(12) **United States Design Patent** (10) Patent No.: **US D501,055 S**
Packard (45) Date of Patent: **** Jan. 18, 2005**

(54) **FLASHLIGHT**

(76) Inventor: **David Packard**, 82 N. Quinsigamond Ave., Shrewsbury, MA (US) 01545

(**) Term: **14 Years**

(21) Appl. No.: **29/203,626**

(22) Filed: **Apr. 16, 2004**

(51) LOC (7) Cl. **26-02**

(52) U.S. Cl. **D26/37**

(58) Field of Search D26/37-50; 362/459-468, 362/473-476, 485-487
